UNITED STATES PATENT OFFICE.

EDWARD F. MONTGOMERY AND AUGUST HEIBERGER, OF SANDUSKY, OHIO;
SAID MONTGOMERY ASSIGNOR TO SAID HEIBERGER.

DEVICE FOR CONVERTING MOTION.

SPECIFICATION forming part of Letters Patent No. 390,502, dated October 2, 1888.

Application filed March 15, 1888. Serial No. 267,259. (No model.)

To all whom it may concern:

Be it known that we, EDWARD F. MONTGOMERY and AUGUST HEIBERGER, both residents of Sandusky, in the county of Erie and State of Ohio, have invented certain new and useful Improvements in Devices for Converting Motion; and we do hereby declare that the following is a full, clear, and exact description of the invention, which will enable others skilled in the art to which it appertains to make and use the same, reference being had to the accompanying drawings, which form a part of this specification, and in which—

Figure 1 is a perspective rear view of our improved device for converting motion. Fig. 2 is a front elevation of the same, showing it as applied to the end of a piston-rod. Fig. 3 is a side elevation, part of the frame being broken away; and Fig. 4 is a horizontal sectional view on line $\alpha\alpha$ in Fig. 3.

Similar letters of reference indicate corresponding parts in all the figures.

Our invention has relation to devices for converting reciprocating motion of steam-engines, &c., into rotary, and vice versa, of that type in which this is effected by means of a cogged pinion or segment engaging cogged racks arranged opposite to each other; and our improvement consists in the detailed construction and combination of parts of a device of that class, as will be hereinafter more fully described, and particularly pointed out in the claims.

Reference being had to the accompanying drawings, the letters A A designate the guideways for the movable reciprocating frame B. The latter, which may be cast in one piece, consists of the two parallel racks C C, which are connected at the top and bottom by the cross-pieces D D. These cross pieces are connected to each other by two bars, designated by the letters E E, and one of them is bolted or otherwise connected to the end of a piston-rod or other reciprocating motor, M. The two bars E E are parallel to each other and to the side racks, C C, but project beyond the plane of the frame B, to the back part of which they are fastened, removably, by means of the screws or bolts F.

The letter G designates the rotary shaft,

which is hung in suitable bearings, H, and is keyed or otherwise fastened at its inner end in the center of the cogged segment I, the cogs or teeth of which may mesh with the cogged racks C C. The central portion of this segment is extended to form a cylindrical projection, (shown at J,) into the central bore of which the shaft is inserted and securely fastened, either by a wedge or key or by means of a binding-screw, K, as shown in the drawings. For the sake of convenience we prefer this latter mode of fastening the shaft to the segment and its cylindrical extension, although it is obvious that other methods may be resorted to, if desired, without departing from the spirit of our invention, so far as this part of it is concerned. This cylindrical extension J is provided with a circumferential groove, L, of suitable depth and of a width corresponding to the thickness of the parallel bars E E, which connect the top and bottom parts of the reciprocating frame, and these bars are so disposed upon the back part of the frame that they will project into the circumferential groove L, one on each side. In this manner it will be seen that these bars operate as guides for the frame to which they are fixed, and of which they form a removable and adjustable part, in such a manner that the reciprocating frame will always work true forward and back when the shaft is rotated without danger of binding against the exterior guideways, A A. In other words, by the employment of these inner guide-bars engaging the grooved projection on the segment, the reciprocating frame will always work parallel to the outer guides without tilting it obliquely on its forward and backward strokes. The apertures at opposite ends of these guide-bars E E, through which the screws F are inserted, are made oblong, in the nature of slots, as indicated in dotted lines on the drawings, so that by loosening the screws at opposite ends the bars may readily be adjusted laterally to compensate for wear.

Having thus described our invention, we claim and desire to secure by Letters Patent of the United States—

1. The combination of the reciprocating cogged frame, the revolving cogged segment, the

grooved cylinder, and the guide-bars fastened upon the reciprocating frame and working in the groove of the cylinder, substantially as and for the purpose shown and set forth.

5 2. The combination of the rotary shaft, the cogged segment provided with a cylindrical extension having a circumferential groove, the reciprocating cogged frame adapted to engage the rotary segment, the exterior parallel guideways, and the parallel and adjustable inner guideways adapted to engage the groove in the cylindrical projection on the segment, all con-

structed to operate substantially in the manner and for the purpose herein shown and set forth.

15

In testimony that we claim the foregoing as our own we have hereunto affixed our signatures in presence of two witnesses.

EDWARD F. MONTGOMERY.
AUGUST HEIBERGER.
